FLUORESCENT ELECTRIC LAMP

Louis Rogers, Brooklyn, N. Y.

Application January 20, 1948, Serial No. 3,281

1 Claim. (Cl. 176—122)

1

This invention relates to fluorescent electric lamps which are designed for attachment at one end to commonly used electric light sockets.

An object of this invention is to provide a fluorescent electric lamp having contacts only at one end of the lamp and which in connection with a suitable choke can be threaded into any standard electric socket.

Another object of this invention is to provide a combined fluorescent electric lamp with an adapter containing a current limiting reactor or resistor.

Another object of this invention is to provide the fluorescent electric lamp with a radioactive and photoelectric coating on the electrodes.

Another object of this invention is to provide the fluorescent electric lamp with a printed path, the resistance of which is higher than the ionized path through the gaseous medium but lower than the non-ionized path through the gaseous medium.

Another object of this invention is to provide a fluorescent electric lamp having a radioactive path which provides a permanent partial ionization of the gaseous medium of the lamp.

Another object of this invention is to provide electrodes made in the form of open coils so that the radioactivity is concentrated within the field of the coils, thereby lowering the work function and facilitating the liberation of electron discharge and causing the electrons to ionize the gas at a faster rate.

With the above and other objects in view, the invention will be hereinafter more particularly described, and the combination and arrangement of parts will be shown in the accompanying drawings and pointed out in the claim which forms part of this specification.

Reference will now be had to the drawings, wherein like numerals of reference designate corresponding parts throughout the several views, in which:

Figure 1 is a fragmentary view of a fluorescent electric lamp and adapter embodying my invention.

Figure 2 is a front elevation of the lamp and adapter, the adapter being partly broken away to show a bayonet type connection.

Figure 3 is a cross-sectional view taken on line 3—3 in Figure 1.

Figure 4 is a fragmentary view of a modified fluorescent electric lamp.

Figure 5 is a cross-sectional view taken on line 5—5 in Figure 4.

Figure 6 is a plan view of a coated electrode, on an enlarged scale.

Figure 7 is a top view of a modified standard having a printed path on one-half of its surface and an alpha active non-conductive coating on the other half of its surface.

2

In the illustrated embodiment of the invention, the numeral 10 indicates a fluorescent electric lamp comprising a sealed envelope or container 11 made of glass or similar material. The lower end is sealed to a stem or support 12. The support 12 protrudes inwardly of the envelope 11.

Two elongated standards 13 are mounted on the support 12. The standards 13 are substantially co-extensive with the length of the glass envelope 11. The standards 13 preferably pass through a support disc 14 and are then bent in a reverse direction and pass through the disc 14 and terminate in extensions 15 which face the support 12. The extensions 15 have an emission electrode or discharge element 16 suitably secured thereto.

Two standards 17 of reduced length are mounted on the support 12 and have an emission electrode or discharge element 16' suitably secured thereto. The upper and lower emission electrodes 16 and 16' are of identical design and preferably of open coil form as shown.

Lead-in wires 20, 21, 22, 23 are connected to the corresponding standards 13 and 17 whereby electrical energy is transmitted to the emission electrodes 16, 16'. The lower end of the lamp 10 terminates in an insulating member 24 and a contact 25.

The emission electrodes 16, 16' have surface coatings 26 which are radioactive and have photoelectric properties. The radioactive coatings ionize the space around each electrode. This results in the easy liberation of electrons under a lower than usual voltage-pressure.

35 In the preferred embodiment of this invention, the standards 13 carry tubular members 27, 27'. The member 27' has a printed path 28 thereon for current flow.

It is to be noted that the printed path 28 has 40 no physical connection to any of the discharge elements 16, 16'. Also, that a leakage gap is provided between the printed path and the adjacent discharge element.

The adapter 30 comprises an outer container 45 31 which carries a socket 32 having a bayonet type connection 33 for the lamp 10 at one end and a screw type plug 34 at the opposite end.

The adapter 30 contains a reactor 35 well known in the art. The remaining space in the 50 adapter is filled with heat conductive material.

It is to be noted that the printed surface forming the printed path is insulated by coating the surface with an insulating material. This insulation extends from electrode to electrode through the ionized medium. The insulation prevents ionization of the structure of the printed resistance path which would otherwise become conductive.

55 Figures 4 and 5 show a modified fluorescent electric lamp 40 having only one elongated stand-

ard 41 which is insulated and supported by a tube 42 made of glass or other insulating material. The tube 42 has a printed path coating 43 on the entire length thereof but on only one-half of its circumference.

The fluorescent electric lamp 40 comprises a sealed envelope or container 44 made of glass or similar material. The lower end of the envelope 44 is sealed to a stem or support 45. The support 45 extends inwardly of the envelope 44.

The standard 41 is mounted on the support 45. The standard 41 is substantially co-extensive with the length of the glass envelope 44. The standard 41 passes through a support disc 46 which is preferably made of mica and is then bent in a reverse direction and passes through the disc 46 and terminates in extensions 47 which face the support 45. The extensions 47 have an emission electrode or discharge element 16 suitably secured thereto.

Two standards 48 of reduced length are mounted on the support 45 and have an emission electrode or discharge element 16' suitably secured thereto. The upper and lower emission electrodes 16 and 16' are of identical design and preferably of open coil form as shown.

Lead-in wires 49, 50 are connected to the corresponding standards 48 whereby electrical energy is transmitted to the emission electrodes 16, 16'. The lower end of the lamp 40 terminates in an insulating member 24' and a contact 25'.

The emission electrodes 16, 16' have surface coatings 26 (Figure 6) which are radioactive and have photoelectric properties. The radioactive coatings ionize the space around each electrode. This results in the easy liberation of electrons under a lower than usual voltage-pressure.

It is to be noted that the printed path 43 has no physical connection to any of the discharge elements 16, 16'. Also, that a leakage gap is provided between the printed path and the adjacent discharge element.

It is to be noted that the insulation coating on the printed path surface terminates slightly below the upper electrode and slightly above the lower electrode to allow a leakage gap.

It is to be noted that the emission electrodes or discharge elements are made in the form of open coils so that the radioactivity and the photoelectric effect is concentrated within the field of the coils, thereby lowering the work function and facilitating the liberation of electron discharge and causing the electrons to ionize the gas in the tube at a faster rate due to the particular form of electrodes shown.

The specific construction of the electrodes here-with shown is more fully disclosed in my patent application for Radioactive electrode coating,

Serial No. 765,341, filed August 1, 1947, now abandoned.

In accordance with the patent statutes I have described and illustrated the preferred embodiments of my invention, but it will be understood that various changes and modifications can be made therein without departing from the spirit of the invention as defined by the appended claim.

10 I claim:

In a fluorescent electric lamp comprising a sealed glass envelope, a support mounted therein, two elongated standards mounted on said support and carrying a discharge element, two 15 standards of reduced length mounted on said support and carrying a discharge element, said elongated standards being of equal length and free of connection with each other to provide an unobstructed electron path between said discharge elements, an ionized gaseous medium within said container, a radioactive coating of 20 electron emitting material on said discharge elements, said coating providing permanent partial ionization of said gaseous medium, said discharge 25 elements being supported by said standards in spaced-apart relation from each other, an insulated semi-conductive printed path on one of said elongated standards lengthwise of said glass envelope for current flow providing a predetermined resistance greater than the ionized path but less than the non-ionized path so that the current seeking least resistance will cause ionization of the gaseous medium, a support disk 30 mounted in said envelope at the end opposite said stem and engaging the side walls of said envelope, said standards passing through said disk and being held in supported relation thereby, 35 said standards having extensions facing in a reverse direction after passing through said disk, 40 said extensions forming carriers for one of said electrodes, and terminal elements connecting said standards to points external of one end of said envelope.

LOUIS ROGERS.
